UNITED STATES PATENT OFFICE.

CLARENCE A. VETTER, OF PITTSBURGH, PENNSYLVANIA.

LAMP-SOCKET.

1,209,908.

Specification of Letters Patent. Patented Dec. 26, 1916.

Application filed December 26, 1913. Serial No. 808,664.

To all whom it may concern:

Be it known that I, CLARENCE A. VETTER, a citizen of the United States, residing at Pittsburgh, in the county of Allegheny and 5 State of Pennsylvania, have invented certain new and useful Improvements in Lamp-Sockets, of which the following is a specification.

My invention refers to improvements in 10 the class of sockets for incandescent lamps.

It has for its object to provide a key-actuated socket adapted to operate for making and breaking the current by partial rotation of the actuating key within the base, 15 the device being provided with co-acting spring-actuated elements, whereby the completion of the operation is effected to insure a quick "make" and "break" of the contact or current establishing mechanism.

20 The invention, as constructed, and for the purpose of accomplishing such objects, consists generally of a base portion of insulating material having the usual terminal connections and the central and screw shell 25 contact portions for engagement with the lamp base; an intermittently operative actuating key and stem; a make-and-break circuit opening and closing device thereon having a lost motion connection with the key; a 30 fixedly attached spring-actuated throw device on the stem; and a lost motion connection between the key and the stem, as shall be more fully hereinafter described.

Referring now to the drawings illustrating one preferred form of the invention, Figure 1 is a vertical sectional view through the socket, indicated by the section line I. I. of Fig. 3. Fig. 2 is a similar vertical sectional view at right angles to Fig. 1, indicated by the section line II. II. of Fig. 3. Fig. 3 is a plan view of the socket. Fig. 4 is a horizontal sectional view, taken on the line IV. IV. of Fig. 1. Fig. 5 is a vertical sectional view through the insulating base portions, indicated by the line V. V. of Fig. 3. Fig. 6 is a partial vertical sectional view, similar to Fig. 2, showing the switch open. Fig. 7 is a perspective detail view of the current establishing key-actuated conductor 50 block. Fig. 8 is a similar view of the spring for the stem controlling block.

In the drawings, the insulating base of the socket is composed of two parts, *a* and *b*, of porcelain or other suitable insulating 55 material, fixedly connected in any suitable

manner, as by screws *c*, the lower base member *b* having the screw shell 2 for receiving the base *d* of the lamp *D* of the usual construction, and having the central contacting terminal portion *d'*. Shell 2 is 60 fixedly connected with base member *b* by screws 3, 3, to one of which, by a binding screw device 4, is connected the terminal of one of the main supply wires *e*. The other contact wire *f* is connected by a binding screw device 5 with an upper spring contact terminal 6, which is fixedly mounted within the upper portion of the socket, and to member *a* thereof, by screw 7. As shown, the inner central portion of members *a* and *b* is hollowed out for clearance 70 of these parts and of the other operating elements, as will be clearly understood.

The preliminary actuating element of the socket is the intermittently rotatable stem 8, 75 mounted in suitable transverse bearing bars 9, 9, inserted between the meeting portions of the base members *a* and *b*, and in receiving sockets therein, whereby the bearings 9 are fixedly held in position. Stem 8 is provided with an actuating finger terminal 10, of suitable insulating material, inwardly from which extends the stud portion 11, embracing the end of stem 8. The stud 11 is provided with transverse slots 12 at one or 80 both sides, into which extend the terminal or terminals of a transverse pin or key 13, which likewise extends through or is fixedly connected with the stem 8.

The purpose of slot 12 is to permit the 85 rotation of stem 8 by the accelerating spring-actuated mechanism for completion of the throw of the stem to effect quick make or break of the contact mechanism, supplemental to the initial turning action 90 by the terminal 10 and its stud 11. For the purpose of effecting such supplemental accelerated movement of stem 8, and its conductor block, I provide a rectangular block 14 fixedly secured or mounted on the stem 100 by soldering or other suitable means, having opposite parallel faces which are normally embraced between the inwardly pressing spring leaves 15, 15, of a resilient clevis, the base 16 of which is fixedly secured to the 105 lower insulating base member *b* by a holding screw 17 or other suitable device.

The conductor block 18, of suitable conducting material, as brass, is loosely mounted upon stem 8, which passes through 110

tral opening 19 therein. The block is provided with a central recess for clearance of a transverse actuating pin 20, adapted to provide for initial movement of pin 20 upon actuation of stem 8, such central clearance being bounded within the opposite transverse shoulders 21, 21, against which the ends of pin 20 bear, at or about the time when the stem 8 has been turned for, say, one-eighth of a revolution, so as to move the controlling block 14 around to the position indicated in dotted lines in Fig. 5. Such action spreads the spring leaves 15, 15, apart, as also indicated in dotted lines, by the separating action of the corners of controlling block 14. The action of springs 15, 15, is such that they will effect the completion of the rotation of the stem 8 upon slightly further movement, and at a greatly accelerated speed, by closing inwardly against the next adjacent parallel sides of the controlling block. This operation thus effects the completion of the one-quarter rotation of the stem, and is performed entirely independent of finger terminal 10, due to the free movement of cross pin 13 in the clearance slot 12. As shown, block 18 is hexagonal in shape, thus providing two faces sloping toward the ends at each side from the widest middle portion. By this construction, the movement of the block and its action with relation to the contact springs 6 and 22 is eased and facilitated, in connection with the controlling block 14 and its own lost motion connection with stem 8. The conductor block 18 is mounted, as described, upon stem 8, for partial lost motion movement thereon, by stem or pin 13, and is itself carried around with the stem, by the action of the controlling block, as described, effecting its corresponding accelerated movement, to make or break the circuit between the co-acting conductor spring members. One of such spring members 6 has been described. The other contact spring member 22, of considerable resiliency, is connected by nut 23 and screw stud 24 through the lower central portion of base member b, with the central contact 25, against which engages the central contact portion d' of the lamp socket d. The range of resilient movement of spring 22 is sufficient to engage against the end of conducting block 18, as in Fig. 2, to transmit the current, and also to engage the side of the block 18 when turned a quarter way around, to open position, whereby to hold it inoperatively for maintaining an open circuit, as in Fig. 6. The construction thus provides for positively holding the conductor

block in either open or closed arrangement.

The construction and operation will be readily understood from the foregoing description. The opposing portions of the conductor block 18, being of a sufficient distance apart, will tightly engage the springs 6 and 22 when in circuit-establishing position, as in Fig. 2, and will be quickly thrust into such position by action of the controlling block 14 and springs 15, 15. Likewise, in opening the circuit, upon partial rotation of the stem by the terminal 10, the completion of the movement is effected by the controlling block, quickly throwing the conductor block around out of contact and to the intermediate position, as shown in Fig. 6.

The operation as thus described is intermittently continuous, effecting a quick make or break of the circuit, upon a preliminary actuation by the operating key, the last portion of the operation being effected automatically in the manner described.

What I claim is:

1. In a lamp socket, the combination of a two-part insulating base, one part thereof having external lamp connecting terminals and each part having a circuit wire terminal, centrally arranged conducting springs, a rotatable elongated hexagonal block therebetween for making and breaking the circuit to one of the lamp terminals, an actuating stem having a lost motion pin-and-shoulder connection with said block, a terminal finger key having a lost-motion connection to the stem, and a spring actuated device for accelerating and arresting the rotation of said stem, substantially as set forth.

2. In a lamp socket, the combination of a two-part insulating base, one part thereof having external lamp connecting terminals and each part having a circuit wire terminal, centrally arranged conducting springs, a rotatable elongated hexagonal block therebetween for making and breaking the circuit to one of the lamp terminals, an actuating stem having a lost motion pin-and-shoulder connection with said block, an actuating finger terminal having a lost motion connection with the key, and a spring actuated device for accelerating and arresting the rotation of said stem, substantially as set forth.

In testimony whereof I hereunto affix my signature in the presence of two witnesses.

CLARENCE A. VETTER.
